UNITED STATES PATENT OFFICE.

BURTEN L. BARTON, OF WENDELL, IDAHO.

CULTIVATOR.

1,258,085.

Specification of Letters Patent.

Patented Mar. 5, 1918.

Application filed May 3, 1917. Serial No. 166,198.

To all whom it may concern:

Be it known that I, BURTEN L. BARTON, a citizen of the United States, residing at Wendell, in the county of Gooding and State of Idaho, have invented new and useful Improvements in Cultivators, of which the following is a specification.

My present invention has relation to cultivators and other land-working machines; 10 and it contemplates the provision of a simple, easily operated and light draft machine, designed and adapted for corrugating land planted with alfalfa and other crops as well as virgin land in such manner as to 15 assure adequate distribution of water and thorough irrigation of the land.

The invention in all of its details will be 20 fully understood from the following description and claims when the same are read in connection with the drawings, accompanying and forming part of this specification, in which:

Figure 1 is a top plan view, partly 25 broken, of the land-working machine constituting the best practical embodiment of my invention that I have as yet devised.

Fig. 2 is a side elevation of the same.

Fig. 3 is a rear end elevation of the machine. 30 Fig. 4 is an enlarged detail view illustrative of the manner of attaching each of the steel points to its complementary channel-form shoe.

Similar numerals of reference designate 35 corresponding parts in all of the views of the drawings.

Among other elements my novel machine comprises a platform-like body 1 which is preferably, though not necessarily, of wood.

40 Fixed to the upper side of the said body or platform 1 and extending forwardly and upwardly therefrom are forwardly converged metallic straps 2 which are pivotally connected at 2^a to metallic uprights 3 and 45 a wooden tongue 4, the latter being inter-

posed between the metallic uprights, and being adapted to be swung vertically on the center 2^a for the purpose hereinafter set forth. The said tongue 4 is shown as provided with a hammer strap, Figs. 1 and 2, for the connection of a double tree (not illustrated) though it is to be understood that the double tree may be connected with the tongue in any other approved manner 55 without affecting my invention.

Fixed to and rising from the platform-

like body 1 and arranged adjacent to the rear end thereof is a loop-shaped upright 5. This upright receives, guides and braces the rear end of the tongue in the vertical movements thereof, and it also serves to support and brace the seat bar 6 which is connected at its forward end between the uprights 3 and is equipped at 7 with a driver's seat of sheet steel or other suitable material. 60

Fixed to and rising from the body 1, at one side of the upright 5, is a segmental rack 12, and journaled in transverse bearings 8 on the body is a transversely-disposed rock shaft which is provided intermediate the said bearings with a loop-shaped crank 9, and is also provided at its 70 ends with a hand lever 11 equipped with a detent for the purpose of adjustably fixing it with respect to the rack. The transverse portion of the crank 9 is arranged and movable in the strap bearing 10 at the underside of the rear portion of the tongue, and consequently it will be manifest that rocking of the lever 11 will be attended by upward and 80 downward movements of the rear portion of the tongue; also, that when the detent of lever 11 is seated in one of the depressions of the rack 12, the tongue 4 will be adjustably fixed with respect to the body 1. 85

Arranged longitudinally at the underside of the body 1 and suitably spaced apart are shoes 14, of channel form in cross-section. These shoes are preferably of cast iron and are fixed to the body 1 in any manner compatible with the purpose of my invention. 90

At their forward ends the shoes 14 are equipped with tempered steel points 16 which have the upwardly and rearwardly inclined portions 15 for the passage of connecting bolts 19 and the lower rearwardly extending portions 17 for the passage of connecting bolts 18, the latter being carried through the channel-form shoes 14 and suitably connected to the body 1 and the 100 braces 2.

As will be understood by comparison of Figs. 1, 2 and 4, the construction, shape and proportional size of the points 16 are such that they readily enter and leave the ground and are also adapted to divide alfalfa roots with a view to making continuous furrows for the shoes 14 to travel in, and this in such manner that but little draft is imposed on the team drawing the machine. 105

In operation when the lever 11 is adjusted forwardly the machine is so manipulated in 110

all of its parts that the points 16 are thrust downwardly so as to enter or penetrate the ground, and when the machine is operated with the points 16 disposed as stated the said 5 points will manifestly cause the shoes 14 to follow in the furrows made by the points with the result that channels are left after the machine through which water will be distributed over the land.

10 When the lever 11 is adjusted rearwardly, the points 16 are raised and thereby enabled to work out of the ground, with the result that corrugating of the land is stopped as is desirable, for instance, when the machine is 15 being turned at the end of the field.

It will be gathered from the foregoing that my novel machine is simple and inexpensive in construction and is light in weight and draft; also, that the machine as a whole 20 is well adapted to withstand the rough usage to which machines of corresponding character are ordinarily subjected.

Having described my invention, what I 25 claim and desire to secure by Letters Patent, is:

1. In a ground working machine, the combination of a body, longitudinally-disposed spaced shoes, of channel-form in cross-section, fixed with respect to the body at the 30 underside thereof, points fixed to the forward ends of the said shoes, a tongue connected with the body, and means connected with the body and the tongue and constructed and arranged to adjust the points of the 35 shoes and also constructed and arranged to adjustably fix the points in the positions in which they are placed.

2. In a ground working machine, the combination of a body, longitudinally-spaced

shoes, of channel form in cross section, fixed 40 with respect to the body at the underside thereof, points fixed to the forward ends of said shoes, braces fixed to and extending forwardly of the body, a tongue pivotally connected at an intermediate point of its length 45 to said braces and arranged to be swung vertically on said pivot, and means on the body and tongue for adjusting and adjustably fixing each with respect to the other.

3. In a ground working machine, the combination of a body, longitudinal, spaced shoes fixed to the body at the underside thereof, said shoes being of channel-form in cross-section and having points at their forward ends, braces fixed to and extending upwardly and forwardly from the body, a vertically swinging tongue pivoted at an intermediate point of its length on said braces, uprights extending upwardly from the braces and tongue, an upright loop fixed on 60 the body and receiving the rear end of the tongue, a bar connected to said uprights and resting on and connected to said loop and extending in rear of the loop and provided with a seat, a segmental rack fixed on the 65 body, a transverse rock shaft journaled in bearings on the body and having a crank and also having a lever equipped with means for engaging the rack, and a strap bearing on the rear portion of the tongue and receiving the crank of the shaft.

In testimony whereof I have hereunto set my hand in presence of two subscribing witnesses.

BURTEN L. BARTON.
